STOKER CONSTRUCTION

Royce L. Beers, Detroit, Mich., assignor to Detroit
Stoker Company, Detroit, Mich., a corporation
of Michigan

Application April 27, 1931, Serial No. 533,341

8 Claims. (Cl. 110—44)

This invention relates generally to stokers and refers more particularly to improved means for controlling the operation of stokers.

The invention finds particular utility when used in connection with mechanical stokers of the type embodying a reciprocable ram and mechanism for intermittently actuating the ram to transfer fuel from a hopper into a retort in accordance with variations in the supply of fuel in the latter. In stokers of the foregoing type it is particularly desirable and advantageous to arrest the ram when the latter is in the throat of the fuel hopper so as to close communication between the latter and retort and thereby prevent the fire in the retort from creeping back into the hopper. Accordingly, it is one of the principal objects of this invention to provide control means for the ram actuating mechanism which, in addition to effecting the desired intermittent operation of the ram, also insures arresting the ram in the aforesaid position.

Another object of this invention is to provide an arrangement of the foregoing type wherein arresting the ram in the throat of the hopper is insured irrespective of the point in the cycle of operation of the ram at which the timing control means functions to discontinue further reciprocation of the ram.

A further object of this invention is to provide a construction of the type specified so designed that arresting of the ram in the throat of the hopper is effected at the end of the power stroke of the ram or, in other words, when the crank for reciprocating the ram is at dead center. The above construction is advantageous since it reduces the starting load on the prime mover for actuating the crank to a minimum.

The foregoing as well as other objects will be made more apparent as this description proceeds, especially when considered in connection with the accompanying drawings, wherein:

Figure 1 is a fragmentary side elevational view partly in section showing one type of stoker with which my improved control means may be used;

Figure 2 is a diagrammatic view of the system employed for controlling the stoker shown in Figure 1;

Figure 3 is an enlarged fragmentary end elevational view of a portion of the stoker actuating mechanism.

Generally described, there is fragmentarily illustrated in Figure 1 a furnace 10 having a retort 11 and a stoker 12 for supplying fuel to the retort. The stoker 12 is located exteriorly of the furnace and comprises a fuel hopper 13 hav-

ing a restricted throat 14 communicating with a ram casing 15 adjacent the entrance to the retort. As is usually the case in constructions of the above type, the fuel from the hopper is transferred to the retort by means of a ram 16 mounted for reciprocation in the ram casing and actuated by a crank shaft 17 having a crank 18 connected to the ram by means of a suitable pitman or connecting rod 19. The foregoing construction is so designed that when the ram 16 is at the limit of its power stroke, it assumes a position across the throat 14 of the hopper so as to close communication between the latter and retort. The ram is shown in the aforesaid position in Figure 1 and the advantage derived by reason of this construction will be more fully hereinafter described.

The crank shaft 17 in the present instance is driven by a constant speed electric motor 20 preferably of the multiphase type and connected to a source of electric energy through a clapper switch 21. The clapper switch 21 is preferably of the magnetically operable type and like the motor 20 is preferably of conventional design.

For controlling the operation of the switch 21 to thereby regulate the operation of the ram 16, the circuit 22 is provided. As shown in Figure 2, this circuit is connected to the source of electrical energy in advance of the clapper switch 21 and supplies current to a solenoid 23 and an automatic adjustable time switch 24. The solenoid 23 is connected in series with the circuit 22 and serves to magnetically hold the clapper switch 21 in its operative position wherein current is supplied to the motor 20. The time switch 24 is of conventional design and is preferably of the motor operated adjustable type comprising a synchronous motor 25 and a switch 26. The motor 25 is connected in parallel with the main circuit or source of electrical energy in advance of the clapper switch 21 and independent of the circuit 22 so as to continuously operate. The motor 25 serves to actuate the adjustable time controlled mechanism (not shown) which in turn functions to periodically actuate the switch 24. The above mechanism is not shown herein since it is part of the standard equipment of conventional adjustable time switches. The switch 24, diagrammatically shown in Figure 2, is preferably of the single pole type and is connected in series with the circuit 22 for opening and closing the same.

It is to be understood from the previous description that the time switch 24 in the present instance functions to automatically start and stop the ram at predetermined intervals depending

upon the particular adjustment thereof which in turn depends upon the particular installation and the rate at which fuel is consumed. The manner in which the time switch 24 functions to periodically actuate the ram is believed obvious from the above. However, assuming that the ram is operating and that the adjusted time interval is up, the switch 24 automatically opens the circuit 22 and since both the latter and solenoid are in series in the circuit 22, it necessarily follows that the solenoid is de-energized permitting the clapper switch 21 to open. Opening of the switch 21 disconnects the ram actuating motor 20 from the source of electrical energy and as a consequence, discontinues further operation of the ram. When the period of rest of the ram has elapsed, the switch 24 automatically closes the circuit 22 permitting the flow of current from the source of supply through the circuit 22 to energize the solenoid 23 and thereby close the clapper switch to connect the ram actuating motor 20 with the source of electrical energy. In connection with the foregoing, it is to be noted that if desired, a three way switch 27 may be placed in the circuit 22 for shunting out the automatic time switch and permitting the system to be actuated manually. As shown in Figure 2, when the switch 27 is in engagement with the contact 28, the control is automatic as previously described, but when the switch engages the contact 29, it forms a shunt across the circuit cutting out the automatic switch 24. When, on the other hand, the switch 27 is moved to a position intermediate the two aforesaid positions, the circuit is broken and operation of the ram discontinued.

While it will be apparent that the above arrangement functions efficiently for automatically and periodically actuating the ram, nevertheless, it is to be noted that with such a construction the ram is arrested as soon as the time interval controlled by the automatic time switch has expired irrespective of the position of the ram in the stoker. In other words, with the construction as thus far described, the ram may be arrested at any point in the cycle of operation thereof which is objectionable since, for example, if the ram is arrested at the end of its return stroke, considerable starting load is placed on the motor for actuating the same and the fire in the retort is free to creep out into the hopper or ram casing.

In order to overcome the above objections, I provide means for insuring arresting of the ram at the end of its power stroke and in a position wherein communication between the hopper and retort is closed irrespective of the position of the ram at the time the automatic time switch or manual switch functions to discontinue operation thereof. The foregoing is accomplished in the present instance by means of a switch 30 arranged in parallel in the circuit 22 between the solenoid 23 and manually operable switch 27 so as to shunt both the latter and automatic switch 24. As shown in Figure 1, the switch 30 is in the form of a limit switch mounted upon the stoker and having an operating arm 31 arranged in the path of travel of a suitable trip 32 movable with the ram. The position of the trip 32 is so selected that when the ram reaches the limit of its power stroke opposite the throat 14 of the hopper, it automatically actuates the arm 31 to open the switch 30. It is to be noted that the disposition of the switch 30 in the circuit 22 is such that opening or closing the same has no effect on the operation of the ram unless the automatic switch 24 or the manually operable

switch 27, depending upon which is in use, has been previously operated to open the circuit. The primary function of the switch 30 as will be apparent from Figure 2 is to maintain the solenoid 23 energized for holding the switch 21 closed until the ram reaches the end of its power stroke across the throat of the hopper, in the event either the switch 27 or switch 24 depending upon which is used is opened at any other point in the cycle of operation of the ram. In other words, before the circuit to the ram actuating motor can be broken, the switch 30 and either of the switches 27 and 24, depending upon which is used, must be opened and since the switch 30 is controlled by the ram, it necessarily follows that arresting of the latter in a predetermined position within the stoker is insured.

Thus, from the foregoing it will be apparent that I have provided means for automatically and periodically actuating the ram of a stoker, together with means controlled by the ram for arresting the same in a predetermined position within the stoker irrespective of the position thereof at the time the means aforesaid functions to discontinue operation thereof.

What I claim as my invention is:

1. In a stoker having a fuel hopper, a ram casing having an opening for receiving fuel from the hopper, a retort for receiving fuel from the casing, a reciprocating ram in the casing controlling communication between the hopper and retort, said ram being operable when at the forward limit of its stroke to close all communication between the hopper and retort, and actuating mechanism for the ram including a rotary shaft, an electric motor for driving said shaft, and a pitman operatively connected to the shaft and ram, a switch controlling the motor, and means for controlling the operation of said switch including a second switch, and means for arresting the ram when it reaches the forward limit of its stroke to cut off all communication between the hopper and retort, including a switch for shunting the second switch, said shunting switch being normally closed and having an operating member, and means movable with the pitman and operable when the ram reaches the forward limit of its stroke to actuate said operating member to open the shunting switch, the construction and arrangement of the switches aforesaid being such that opening and closing the shunting switch has no effect upon the operation of the ram unless the second switch aforesaid is open.

2. In a stoker having a fuel hopper, a ram casing having an opening for receiving fuel from the hopper, a retort for receiving fuel from the casing, a reciprocating ram in the casing controlling communication between the hopper and retort, said ram being operable when at the forward limit of its stroke to close all communication between the hopper and retort, and actuating mechanism for the ram including a rotary shaft, an electric motor for driving said shaft, and a pitman operatively connected to the shaft and ram, a switch controlling the motor, and means for controlling the operation of said switch including an automatic time switch, a manually operable switch for shunting the time switch, and means for arresting the ram when it reaches the forward limit of its stroke irrespective of the position thereof at the time either the time switch or the manually operable switch depending upon which is used is opened, said

- last mentioned means being under the control of and rendered effective by said pitman.
3. In a stoker having a fuel hopper, a ram casing having an opening for receiving fuel from the hopper, a retort for receiving fuel from the casing, a reciprocating ram in the casing controlling communication between the hopper and retort, said ram being operable when at the forward limit of its stroke to close all communication between the hopper and retort, and actuating mechanism for the ram including a rotary shaft, an electric motor for driving said shaft, and a pitman operatively connected to the shaft and ram, a switch controlling the motor, and means for controlling the operation of said switch including an automatic time switch, and means for arresting the ram when it reaches the forward limit of its stroke to cut off all communication between the hopper and retort, including a switch for shunting the time switch, said shunting switch being normally closed and having an operating member, and means movable with the pitman and operable when the ram reaches the forward limit of its stroke to actuate said operating member to open said shunting switch, the construction and arrangement of the switches aforesaid being such that opening and closing the shunting switch has no effect upon the operation of the ram unless the time switch is open.
4. In a stoker having a fuel hopper, a ram casing having an opening for receiving fuel from the hopper, a retort for receiving fuel from the casing, a reciprocating ram in the casing controlling communication between the hopper and retort, said ram being operable when at the forward limit of its stroke to close all communication between the hopper and retort, and actuating mechanism for the ram including a rotary shaft, an electric motor for driving said shaft, and a pitman operatively connected to the shaft and ram, a switch controlling the motor, and means for controlling the operation of said switch including an automatic time switch, a manually operable switch for shunting the time switch, and means for arresting the ram when it reaches the forward limit of its stroke to cut off all communication between the hopper and retort, including a trip movable with the pitman and a switch for shunting both the manually operable and time switches, said last mentioned switch being opened by the trip when the ram reaches the forward limit of its stroke and automatically closed when free of the trip, the construction and arrangement of the switches aforesaid being such that opening and closing the last mentioned switch has no effect upon the operation of the ram unless either the time switch or the manually operable switch depending upon which is used is open.
5. In a stoker having a fuel hopper, a ram casing having an opening for receiving fuel from the hopper, a retort for receiving fuel from the casing, a reciprocating ram in the casing controlling communication between the hopper and retort, said ram being operable when at the forward limit of its stroke to close all communication between the hopper and retort, and actuating mechanism for the ram including a rotary shaft, an electric motor for driving said shaft, and a pitman operatively connected to the shaft and ram, a switch controlling the motor, and means for controlling the operation of said switch including a second switch, and means for arresting the ram when it reaches the forward limit of its stroke to cut off all communication be-
- tween the hopper and retort, including a switch for shunting the second switch, said shunting switch being under the control of the pitman so as to be opened when the ram reaches the forward limit of its stroke and being automatically closed, the construction and arrangement of the switches aforesaid being such that opening and closing the last mentioned switch has no effect upon the operation of the ram unless the second switch aforesaid is open.
6. In a stoker having a fuel hopper, a ram casing having an opening for receiving fuel from the hopper, a retort for receiving fuel from the casing, a reciprocating ram in the casing controlling communication between the hopper and retort, said ram being operable when at the forward limit of its stroke to close all communication between the hopper and retort, and actuating mechanism for the ram including a rotary shaft, an electric motor for driving said shaft, and a pitman operatively connected to the shaft and ram, a switch controlling the motor, and means for controlling the operation of said switch including an automatic time switch, a manually operable switch for shunting out the time switch, and means for arresting the ram when it reaches the forward limit of its stroke to cut off all communication between the hopper and retort, including a switch for shunting both the manually operable switch and time switch, said second named shunting switch being normally closed and having an operating member, and means movable with the pitman and operable when the ram reaches the forward limit of its stroke to actuate said operating member to open said second named shunting switch, the construction and arrangement of the switches aforesaid being such that opening and closing the second named shunting switch has no effect upon the operation of the ram unless either the time switch or the manually operable switch depending upon which is used is open.
7. In a stoker having a fuel hopper, a ram casing having an opening for receiving fuel from the hopper, a retort for receiving fuel from the casing, a reciprocating ram in the casing controlling communication between the hopper and retort, said ram being operable when at the forward limit of its stroke to close all communication between the hopper and retort, and actuating mechanism for the ram including a rotary shaft, an electric motor for driving said shaft, and a pitman operatively connected to the shaft and ram, a switch controlling the motor, and means for controlling the operation of said switch including an automatic time switch, a manually operable switch for shunting the time switch, and a switch for shunting both the manually operable switch and time switch, said second named shunting switch being under the control of the pitman so as to be opened when the ram reaches the forward limit of its stroke and being automatically closed, the construction and arrangement of the switches being such that opening and closing the second named shunting switch has no effect upon the operation of the ram unless either the time switch or the manually operable switch depending upon which is used is open.
8. In a stoker having a fuel hopper, a ram casing having an opening for receiving fuel from the hopper, a retort for receiving fuel from the casing, a reciprocating ram in the casing controlling communication between the hopper and retort, said ram being operable when at the forward limit of its stroke to close all communication between the hopper and retort, and actuating mechanism

- for the ram including a rotary shaft, an electric motor for driving said shaft, and a pitman operatively connected to the shaft and ram, a switch controlling the motor, and means for controlling the operation of said switch including an automatic time switch, a manually operable switch for shunting the time switch, and means for arresting the ram when it reaches the forward limit of its stroke to cut off all communication between the hopper and retort including a switch for shunting both the time and manually operable

switches, said second named shunting switch being under the control of the pitman so as to be opened thereby when the ram reaches the forward limit of its stroke and being automatically closed, the construction and arrangement of the switches aforesaid being such that opening and closing the second named shunting switch has no effect upon the operation of the ram unless either the time switch or the manually operable switch depending upon which is used is open.

ROYCE L. BEERS.
